UNITED STATES PATENT OFFICE.

JOHN T. WALSH, OF EAST ORANGE, NEW JERSEY, ASSIGNOR TO INDIAN REFINING CO.,
OF NEW YORK, N. Y., A CORPORATION OF MAINE.

ADVERTISING DEVICE.

1,179,056.

Specification of Letters Patent. Patented Apr. 11, 1916.

Application filed July 8, 1914. Serial No. 849,741.

To all whom it may concern:

Be it known that I, JOHN T. WALSH, a citizen of the United States, residing in East Orange, in the county of Essex and 5 State of New Jersey, have invented a new and useful Improvement in Advertising Devices, of which the following is a specification.

My invention relates in general to advertising devices and more particularly to devices provided for the advertisement of oils, varnishes and other liquids ordinarily packaged in sheet metal cans or containers.

One of the principal objects of my invention is the provision of an advertising device of the character described which will be effective and distinctive in appearance, readily impressing itself upon the mind of an observer and which may be conveniently 20 and compactly packed for shipment and readily assembled for advertising use.

Other objects and advantages of the invention will be apparent as it is better understood from the following description 25 when considered in connection with the accompanying drawing illustrating a preferred embodiment thereof.

On the drawing, Figure 1 is a front elevation of an advertising device embodying 30 my invention; Fig. 2 is a top plan view of the same; and Fig. 3 is a horizontal sectional view taken substantially on the line 3—3 of Fig. 1.

The advertising device shown on the drawing is particularly adapted for the advertisement of oils, varnishes and other liquids and other materials and substances of liquid form which are marketed in sheet metal cans or containers. Bottles 4 are provided, in which the particular brand or oil or varnish or other material ordinarily marketed in the can and being advertised may be displayed. A can 6, resembling in shape and general appearance the can in which the 45 oil, varnish or other material is marketed, is provided in connection with the bottles 4, the can preferably being a miniature reproduction of the actual can used in marketing the material. The can 6 preferably has a 50 removable cover 7 upon which are formed reproductions of the ordinary screw cap 8 and the lifting ring or bail 9. In each side of the body portion 9 of the can and extending downwardly from the top of this body

portion is provided a slot or opening 10 in 55 which is engaged the two ends 11 of fastening clips or bands 12 each of which secures a bottle 4 in position. The height of the body portion of the container is preferably greater than the height of the bottles, and 60 the bands 12 support the bottles somewhat above the base of the container. The container or can is preferably of a proper size to permit the bottles 14 to be positioned within it during shipment, so that when the 65 device is packed it occupies no more space than that taken up by the can itself.

Two different grades of the same material or two different materials which are packaged for the trade in cans of the type used, 70 may be advertised at the same time by the device described, one kind or grade being placed in each bottle. The number of bottles may be increased for other grades or materials if desired and labels 5 may be 75 affixed to the bottles to differentiate the grades or materials.

It will be apparent that when the bottles are secured to the can the whole device will present a pleasing and distinctive appearance, 80 prominently displaying the container and permitting a close inspection of the materials sold in said container, so that both the materials and the packages in which they are marketed will be firmly impressed 85 upon the mind of observers.

It will be obvious moreover that various changes may be made in the form, construction and arrangement of the parts without departing from the spirit and scope of the 90 invention or sacrificing any of its material advantages, the form hereinbefore disclosed being merely a preferred embodiment thereof.

I claim:

A combined advertising device and display rack for oil, varnish or other liquid products; comprising bottles or other transparent containers for the display of the oil or product to be advertised; a sample or 100 fac-simile of the metallic or otherwise non-transparent container in which the goods advertised are retailed, supporting the transparent containers on itself and thereby affording a solid base for the same, having 105 a removable cover, adapted to receive the transparent containers for purposes of shipment, having an opening in either side near

its top; and detachable means consisting of a metallic band adapted to embrace the necks of the transparent containers and to be deposited through the openings in the metallic container and by process of bending, hold the transparent containers in position and at the same time readily detachable.

Signed this 29th day of June, 1914, in the presence of two witnesses.

JOHN T. WALSH.

Witnesses:

EDMUND C. STANTON,
C. W. GRAHAM.
